WILLIAM H. ROSE, OF JERSEY CITY, NEW JERSEY

CLOSURE VALVE

Application filed March 18, 1929. Serial No. 347,820.

My invention relates to container closure-valves and refers particularly to closure-valves suitable for use with inverted liquid-holding containers.

- 5 Liquid-soap dispensers are among the most generally employed inverted liquid-holding containers, and the device of my invention is particularly adaptable for use with such dispensers.
- 10 A closure-valve for the purposes mentioned should be a perfect closure against escape of the soap-liquid, when in normal position, should be readily opened by the hand intended to catch the escaping liquid, should be 15 free from metal to prevent rusting, should be free from springs and similar moving parts, should be of such material and construction as to prevent sticking of the moving parts, should be of such construction that soap deposited upon the exterior thereof shall be as 20 invisible as possible from ordinary observation, should allow of free gravity exit movement of the liquid, should be economic in production and simple in operation.
- 25 All of the above mentioned, and other, valuable attributes are possessed by the device of my invention, as will be evident upon a consideration of my specification and its accompanying drawings.
- 30 In the accompanying drawings, illustrating one form of the device of my invention, similar parts are designated by similar numerals.

Figure 1 is a front view of one form of my device.

Figure 2 is a side view of Figure 1.

Figure 3 is a vertical cross-section of the closure-valve of Figure 2.

Figure 4 is a bottom view of Figure 3.

40 Figure 5 is a side view, partly in section, of the valve of Figure 2 in open position.

Figure 6 is a bottom view of Figure 5.

The accompanying drawings illustrate one form of the device of my invention as applied 45 to one form of a liquid container and comprises a bracket 10, having the annular internally threaded member 11, and having an annular opening 12 therein.

The particular form of my valve device, 50 shown in the accompanying drawing, com-

prises a body member 13 having the annular flange 14, the annular recess 15, the side recess 16 and the extended operating lip 17. An opening, or conduit, 18, extends downwardly through the flange 14 and the body 13, the 55 lower portion 19 of the conduit being of smaller diameter than the upper portion thereof.

The above described valve is so positioned that the flange 14 rests within, and upon, the 60 member 11, the recess 15 being beneath the member 11.

The container 20 has a downwardly extended outwardly threaded neck 21, and an opening 22 with a screw cover 23. 65

The lower edge of the container neck 21 thus presses downward upon the flange 14 and maintains the valve in position.

In operation, liquid is placed in the container 20, a portion of the liquid passing 70 into, and being retained within, the conduit 18.

When it is desired to obtain some of the liquid, the operating lip 17 is pressed upwardly, preferably into the recess 16, this 75 movement opening the conduit 19, as shown particularly in Figures 5 and 6, thus allowing the liquid to pass outwardly therethrough.

When the lip 17 is released, the resiliency 80 of the material from which the valve is composed causes it to return to its original position, thus closing the conduit 19, interrupting the flow of the liquid.

It will be noted from the above that my 85 device is composed entirely of metallic-free resilient material, such as rubber, that the resiliency of the material forms a perfect closure, allows the opening of the exit conduit and re-closes the opening, that the exit opening is at the bottom of the valve, thus allowing a free downward gravity movement of the liquid when open and that any liquid deposited upon the exterior portion of the device at the opening is hidden from ordinary 90 observation.

Further, the construction of my device is such that it can be readily opened by the hand receiving the liquid, and it is to be further noted that the exit, being positioned at the 100

bottom of the device, will not have as great a tendency to tear, or rupture, during repeated use, as is present when the opening, or exit, is in the side of the valve.

5 I do not limit myself to the particular size, shape, number, position or material of parts, mentioned and described, as these are given simply as a means for clearly describing the device of my invention.

10 What I claim is:—

1. In a closure-valve, in combination, a resilient body member having a practically straight longitudinal conduit therethrough, said body conduit being open at one end and having a downwardly extended opening in the lowest portion of the other end thereof, said latter opening being normally closed by the resiliency of the body material and means the movement of which will open the normally closed end of said body conduit without constricting said conduit.

2. In a closure-valve, in combination, a resilient body member having a practically straight longitudinal conduit therethrough, said conduit being open at one end and having a downwardly extended opening in the lowest portion of the other end thereof, said latter opening being normally closed by the resiliency of the body material, the lower portion of said conduit being of smaller diameter than the other portion of said conduit, and means the movement of which will open the normally closed end of said body conduit without constricting said conduit.

3. In a closure-valve, in combination, a resilient body member having a practically straight longitudinal conduit therethrough, said conduit being open at one end and having a downwardly extended opening in the lowest portion of the other end thereof, said latter opening being normally closed by the resiliency of the body material, and means carried by the body member, the movement of which will open the normally closed end of said body conduit without constricting said conduit.

4. In a closure-valve, in combination, a resilient body member having a practically straight longitudinal conduit therethrough, said conduit being open at one end and having a downwardly extended opening in the lowest portion of the other end thereof, said latter opening being normally closed by the resiliency of the body material, the lower portion of said conduit being of smaller diameter than the other portion of said conduit and means carried by the body member the movement of which will open the normally closed end of said body conduit without constricting said conduit.

5. In a closure-valve, in combination, a resilient body member having a practically straight longitudinal conduit therethrough, said conduit being open at one end and having a normally closed opening at the extreme

other end, and an extended lip to said body a movement of which will open the normally closed end of said body conduit without constricting said conduit.

6. In a closure-valve, in combination, a resilient body member having a practically straight longitudinal conduit therethrough, said conduit being open at one end and having a normally closed opening at the extreme other end, a flange carried by said body and having an open conduit therethrough communicating with the open end of said body conduit and an extended lip to said body a movement of which will open the normally closed end of said body conduit without constricting said conduit.

7. In a closure-valve, in combination, a resilient body member having a practically straight longitudinal conduit therethrough, said conduit being open at one end and having a normally closed opening at the extreme other end and an angularly positioned extended lip to said body a movement of which will open the normally closed end of said body conduit without constricting said conduit.

8. In a closure-valve, in combination, a resilient body member having a practically straight longitudinal conduit therethrough, said conduit being open at one end and having a normally closed opening at the extreme other end, a flange carried by said body and having an open conduit therethrough communicating with the open end of said body conduit and an angularly positioned extended lip to said body a movement of which will open the normally closed end of said body conduit without constricting said conduit.

9. In a closure-valve, in combination, a resilient body member, having a practically straight longitudinal conduit therethrough, said conduit being open at one end of said body and having a normally closed opening at the extreme other end of said body, the lower portion of said conduit being of smaller diameter than the remainder of said conduit, and an extended lip to said body, the upward movement of which will open the closed end of said body conduit, allowing the gravitational passage of a liquid therethrough and outwardly of the bottom of said body.

10. In a closure-valve, in combination, a resilient body member, having a practically straight longitudinal conduit therethrough, said conduit being open at one of said body and having a normally closed opening at the extreme other end of said body, the lower portion of said conduit being of smaller diameter than the remainder of said conduit, and an angularly positioned extended lip to said body, the upward movement of which will open the closed end of said body conduit, allowing the gravitational passage of a liquid therethrough and outwardly of the bottom of said body.

11. In a closure-valve, in combination, a resilient body member, having a practically straight longitudinal conduit therethrough, said conduit being open at one end of said body and having a normally closed opening at the 5 extreme other end of said body, the lower portion of said conduit being of smaller diameter than the remainder of said conduit, a flange carried by said body and having an open conduit therethrough communicating with the open end of said body conduit and an extended lip to said body the upward movement of which will open the closed end of said body conduit allowing the gravitational 10 passage of a liquid therethrough and outwardly of the bottom of said body.

12. In a closure-valve, in combination, a resilient body member, having a practically straight longitudinal conduit therethrough, 20 said conduit being open at one end of said body and having a normally closed opening at the extreme other end of said body, the lower portion of said conduit being of smaller diameter than the remainder of said conduit, a flange carried by said body and having an open conduit therethrough communicating with the open end of said body conduit and an angularly positioned extended lip to said body the upward movement of which will 25 open the closed end of said body conduit allowing the gravitational passage of a liquid therethrough and outwardly of the bottom of said body.

13. In a closure-valve, in combination, a resilient body member, having a practically straight longitudinal conduit therethrough, 35 said conduit being open at one end of said body and having a normally closed opening at the extreme other end of said body, the lower portion of said conduit being of smaller diameter than the remainder of said conduit, said body having a recess in the side thereof and an extended lip to said body the upward movement of which will insert said lip in said 40 side recess and open the closed end of said body conduit allowing the gravitational passage of a liquid therethrough and outwardly of the bottom of the body.

14. In a closure-valve, in combination, a resilient body member having a practically straight longitudinal conduit therethrough, 50 said conduit being open at one end of said body, and having a normally closed opening at the extreme other end of said body, the lower portion of said conduit being of smaller diameter than the remainder of said conduit, said body having a recess in the side thereof, a flange carried by said body and 55 having an open conduit therethrough communicating with the open end of said body conduit and an extended lip to said body the upward movement of which will insert said lip in said side recess and open the closed 60 end of said body conduit allowing the passage 65 of a liquid therethrough and outwardly of the bottom of said body.

sage of a liquid therethrough and outwardly of the bottom of said body.

Signed at New York city, in the county of New York and State of New York, this 16th day of March, 1929.
